CLAIM

We claim the ornamental design for clip, as shown and described.

DESCRIPTION

FIG. 1 is a perspective view of the clip.

FIG. 2 is an elevational view of the clip.

FIG. 3 is a bottom plan view of the clip.

FIG. 4 is a top plan view of the clip.

FIG. 5 is a cross-sectional view of the clip taken along line V-V of FIG. 4; and,

FIG. 6 is a cross-sectional view of the clip taken along line VI-VI of FIG. 4.

The dashed lines are for illustrative purposes only and form no part of the claimed invention.

1 Claim, 3 Drawing Sheets
